United States Patent Office.

RUDOLPH BOEHM, OF CHICAGO, ILLINOIS.

Letters Patent No. 90,227, dated May 18, 1869.

IMPROVED ORE-WASHER.

The Schedule referred to in these Letters Patent and making part of the same.

To all whom it may concern:

Be it known that I, RUDOLPH BOEHM, of Chicago, in the county of Cook, and State of Illinois, have invented a new and improved Continuous Ore-Washer; and I do hereby declare that the following is a full, clear, and exact description thereof, which will enable others skilled in the art to make and use the same, reference being had to the accompanying drawings, and letters marked thereon, making a part of this specification, in which—

Figure 1 is a vertical longitudinal section of my invention taken on the line x x , fig. 2.

Figure 2, a plan or top view of the table, water-trough, and sluice, with the upper part of the framework removed.

Figures 3 and 4 are elevations of the ends of the washer.

Figure 5, a perspective representation of the cam-shaft which gives a reciprocating motion to the table.

The present invention relates to an improvement in that class of ore-washers which are more especially designed to separate fine particles of precious metals from silica, sand, loam, or clay, or from any other simple or compound substance; and

Its nature consists in an inclined table, which is divided into two or more equal compartments hung to a frame, and arranged to have a longitudinal motion by means of a cam-shaft and spring, said table supporting two or more sluices, in which the crude material is put, and also a perforated spout for equalizing the flow of water over the table while the ore is being separated.

g represents a substantial foundation, which is made of wood, or other suitable material, and supports two central posts q , and four posts q , the latter being inclined inward longitudinally with said foundation, for the better support of the side beams p , fig. 1, and the end ties p' , figs. 3 and 4.

A table, W , figs. 1, 2, 3, and 4, made of wood or iron, (according to the durability required,) is properly strengthened with cross-beams Z underneath, and so suspended with screw-rods O O , fig. 1, fastened to the edges of the table at e , fig. 2, and put through the beams p , that it has a suitable inclination to carry any substance thereon over its edge, and into a suitable receptacle used to receive it, said table being divided into two or more compartments by means of the strips D , shown at figs. 1, 2, 3, and 4, in order that the metal may be gathered at suitable places, as hereinafter shown under the head of operation.

The table at its upper edge supports two sluices, f , in which the substance to be separated is put preparatory to its passing through the openings 11 and on to the table.

And above it is suspended, by means of iron straps 4, a spout, e , figs. 1 and 2, which has perforations

in its bottom, through which water passes on to the table.

The screw-rods O O may be so adjusted by turning the swivels as to give to the table, when it is desired, a greater or less inclination, according to the nature of the substance from which the ore is to be separated.

A substantial bed-piece, E , fig. 1, is placed longitudinally with and fastened to the underside of the table W , and it supports three or more T-shaped brackets F , through which a screw-rod, m , is put, the function of said rod being hereinafter shown.

K , figs. 1, 2, and 3, represents what I term a bumper, rigidly fastened to the foundation g , and has an iron nose-piece, i , figs. 1 and 2, fastened to it, in order that it may withstand the concussion caused by the table striking against it.

A shaft, n , figs. 1 and 5, runs in suitable bearings, fastened to the foundation, and it supports a cam, h , which is used to give a reciprocating motion to the table W .

And to accomplish this, a plate, l , jointed to the nosing i , extends downward, and between the cam 2 and the end of the screw-rod m , and it is made to vibrate by means of said cam, and give the rod m a reciprocating motion, and consequently communicate the same motion to the table W .

A spring, r , figs. 1 and 2, being attached to a post, q' , and bearing against the end of the bed-piece E , throws the table back at each successive turn of the cam.

The shaft n is to have about three hundred revolutions to the minute, and the power is applied to the end 3 by any ordinary method usually employed for a similar purpose.

Operation.

By this means for operating the table W it is forced back from the cam 2 very gently; but on its return it is stopped suddenly by means of the bumper K .

If a shorter stroke of the table be required, the screw-rod m can be so turned back from the plate l , that it will receive only a partial stroke of the cam.

This adjustment is necessary to adapt the washer to the separating of all kinds of ores taken from mixed substances.

Pulverized rock, sand, or other substance having the ore should be first mixed with sufficient water to make it run slowly. It is then conveyed to the sluices f by means of a spout, or otherwise, as most convenient.

The table is then put in motion by means of the cam aforesaid, and the substance to be washed (by its own specific gravity) gradually passes to the lower edge of the table, and falls off, the lighter substance passing in the direction indicated by the darts 5, and

the heavier in the direction of the darts A *d* and B *d*, as shown at fig. 2, while at the same time sufficient water is made to pass through the perforated spout *e* to liquefy the substance.

Having thus fully described my invention,

What I claim, and desire to secure by Letters Patent of the United States, is—

1. The combination of the table W, screw-rods O, suspended water-trough *e*, and sluices *f*, as and for the purpose set forth.

2. The combination of the cam 2, shaft *n*, bumper K, depending-plate *l*, T-brackets F, screw-rod *m*, spring *r*, table W, sluices *f*, and suspended trough E, as described.

RUDOLPH BOEHM.
